UNITED STATES PATENT OFFICE

MELITTA KLEIN, OF VIENNA, AUSTRIA, ASSIGNOR TO RUTH-ALDO COMPANY, INC., OF NEW YORK, N. Y.

APPARATUS FOR SPINNING SOLUTIONS OF CELLULOSE ETHERS OR ESTERS

Application filed March 27, 1928, Serial No. 265,156, and in France July 6, 1927.

The specification of my pending patent application No. 265,158 filed Mar. 27, 1928 describes a chamber or cell for spinning cellulose ethers or esters in a downward direction, characterized by the fact that it is divided into two or more superimposed zones by one or more diaphragms, the upper zone containing the spinning nozzle being provided with intakes for cold air in proximity to the latter, and the bottom zone, in which the heating is effected, being provided with one or more aspiration orifices.

With this arrangement the air admitted into the upper zone passes through the diaphragm and enters the lower zone, whereas the hot air contained in this latter zone cannot pass into the upper zone, so that the spinning nozzle, and also the thread during the first stage of its travel, are maintained at the temperature of the outer air admitted into said upper zone.

According to the present invention, each zone of the spinning cell or chamber is provided with orifices for the admission and discharge of air, so that the circulation of the air and vapors of solvent in each of the zones is entirely independent of the circulation in the other zones and without appreciable influence on such circulation.

In order to bring about these mutually independent circulations, the same air may be employed in the successive circulations, that is to say, whilst maintaining an independent circuit in each zone, the air which has been admitted into and discharged from one zone may enter a second zone and, on issuing therefrom, be passed, or not, through the other zones.

It is even possible (and may, in certain cases, be advantageous) to subject said air, either prior to its admission into a zone or after issuing therefrom, or at any point during its passage, to any suitable physical action, with the view, for example, of modifying its temperature or the degree of concentration of the vapors of the solvent; or again, to add to said air, at any desired point of its passage, vapors or gases of suitable nature for exercising any desired physical, chemical or other action on the thread.

Some embodiments of spinning chambers according to the present invention will now be described with reference to the accompanying drawings.

Fig. 1 is a vertical section through a chamber provided with a horizontal diaphragm obstructing the whole cross section of said chamber; Fig. 2 represents, also in vertical section, a chamber provided with an oblique diaphragm; Figs. 3 to 5 are diagrams showing means enabling the same air to be utilized for the circulation in each zone of the spinning chamber.

In the various figures, ABCD represents the spinning cell or chamber, F the spinning nozzle, H the thread, I a thread guide, and G the orifice through which the thread passes out. MN represents a diaphragm in the spinning cell or chamber.

In the embodiment shown in Fig. 1, the diaphragm MN is horizontal and extends between the two walls AC and BD of the spinning cell or chamber, so as to divide the latter into two distinct superimposed zones or compartments, the thread H passing through an orifice Z in the diaphragm. The upper compartment, which contains the spinning nozzle F and is provided with orifices E for the admission of cold air, is also provided with an aspiration orifice J, pierced in the wall BD of the cell. Hot air enters the lower zone or compartment through orifices K provided in the bottom CD; and aspiration is effected through a convenient number of orifices, such as L, also provided in the wall BD.

In the embodiment shown in Fig. 2, the diaphragm MN is oblique and the aspiration, at J, of the air entering the upper zone through the orifices E, is effected by means of a tube J¹, which rests on the diaphragm and the mouth J² of said tube is situated at a suitable distance from the thread H. Hot air is admitted into the lower zone through orifices K, as before, and passes out through any convenient number of orifices L provided in the walls AC and BD of the spinning cell or chamber.

From the foregoing it will be evident that the spinning cell or chamber in each of

the embodiments described comprises two air circuits arising from two different sources; but, as already indicated, the same air may be utilized and caused to circulate through the various compartments of the cell, with modification of its physical conditions as, for example, its temperature, at a convenient point in its circuit.

In the form represented in Fig. 3, the upper compartment of the cell receives, at E, cold air which issues from said compartment at J, and passes through a heating apparatus V of any kind, to enter the lower compartment, at a suitable temperature, by way of the orifice K, from which compartment it issues, laden with vapors of solvent, through the orifice L, and is led to the recovery apparatus.

According to Fig. 4, the air, which has previously been raised to the desired temperature by any convenient means, is admitted into the lower compartment of the cell through the orifice or passage K, and issues from said compartment by way of the tube L. It traverses a cooler V, of any type whatsoever, and enters, by way of the tube or orifice E, into the upper compartment, from which it is led to the recovery apparatus through the aspiration branch J.

Finally, Fig. 5 shows a modification in which the air follows, in the two zones of the cell, the same circuit as in Fig. 3, but receives, at a given point in its course, a fluid, gas or vapor, which is introduced through the tube X into the branch X¹, and mixes with the air prior to entering the lower compartment, the atmosphere of which latter also differs in composition from that in the upper compartment.

It will be understood that the arrangements described are given merely by way of example, and that the forms, materials and dimensions of the constituent parts, and also the details of construction, may be modified without departing from the scope of the invention. In particular, the methods of air circulation described with reference to Figs. 3 to 5 may be replaced by any others of any suitable kind which maintain different atmospheres at different temperatures or other physical conditions in different zones of the spinning cell.

I claim:—

1. Apparatus for spinning cellulose ethers or esters, comprising a spinning cell, means dividing the cell into separate zones to be successively traversed by the spun thread passing through said cell, and a spinning nozzle located in one of said zones, said zones having admission and discharge orifices to provide separate circuits, one through each zone in the cell, for the circulation of air and solvent vapors.

2. Apparatus for spinning cellulose ethers or esters, comprising a spinning cell, means

dividing the cell into superimposed zones to be successively traversed by the spun thread, and a spinning nozzle in the uppermost zone, each of said zones having admission and discharge orifices to permit the circulation of air and solvent vapors there-through.

3. Apparatus for spinning cellulose ethers or esters, comprising a spinning cell, at least one diaphragm dividing the cell into superimposed compartments to be successively traversed by the spun thread, and a spinning nozzle in the uppermost compartment, each of said compartments having admission and discharge orifices to permit the circulation of air and solvent vapors.

4. Apparatus for spinning cellulose ethers or esters, comprising a spinning cell, a diaphragm dividing the cell into two superimposed compartments to be successively traversed by the spun thread, and a spinning nozzle in the upper compartment, the upper compartment having an inlet for cold air adjacent the spinning nozzle and an outlet orifice, and the lower compartment having an inlet for hot air and an outlet orifice.

5. Apparatus for spinning cellulose ethers or esters, comprising a spinning cell, means dividing the cell into superimposed compartments to be successively traversed by the spun thread, a spinning nozzle in the uppermost compartment, and means whereby air can be circulated in separate circuits through the compartments one after another.

6. Apparatus for spinning cellulose ethers or esters, comprising a spinning cell, means dividing the cell into superimposed compartments to be successively traversed by the spun thread, a spinning nozzle in the uppermost compartment, and means whereby air from a single source can be circulated successively through the compartments.

7. Apparatus for spinning cellulose ethers or esters, comprising a spinning cell, means dividing the cell into superimposed compartments to be successively traversed by the spun thread, a spinning nozzle in the uppermost compartment, means whereby air from a single source can be successively circulated through all the compartments, and means for modifying the air in its course.

8. Apparatus for spinning cellulose ethers or esters comprising a spinning cell, means dividing the cell into superimposed compartments to be successively traversed by the spun thread, a spinning nozzle in the uppermost compartment, means whereby air from a single source can be successively circulated through each of the compartments, and means for modifying the air in its course.

9. Apparatus for spinning cellulose ethers or esters, comprising a spinning cell, means dividing the cell into superimposed compartments to be successively traversed by the

spun thread, a spinning nozzle in the uppermost compartment, means whereby air from a single source can be successively circulated through all the compartments, and 5 means for modifying the temperature of the air in its course.

10. Apparatus for spinning cellulose ethers or esters, comprising a spinning cell, means dividing the cell into superimposed compartments to be successively traversed by the spun thread, a spinning nozzle in the uppermost compartment, means whereby air from a single source can be successively circulated through all the compartments, and 15 means for modifying the composition of the air in its course.

11. Apparatus for spinning cellulose ethers or esters, comprising a spinning cell, means dividing the cell into superimposed compartments to be successively traversed by the spun thread, a spinning nozzle in the uppermost compartment, means whereby air from a single source can be successively circulated through all the compartments, and 20 means for modifying both the temperature and the composition of the air in its course.

12. Apparatus for spinning cellulose ethers or esters, comprising a spinning cell, means dividing the cell into superimposed compartments to be successively traversed by the spun thread, a spinning nozzle in the uppermost compartment, piping establishing communication between the compartments, an air inlet to one compartment and 35 an outlet from another compartment, and a heat exchanger associated with the piping.

13. Apparatus for spinning cellulose ethers or esters, comprising a spinning cell, means dividing the cell into superimposed compartments to be successively traversed by the spun thread, a spinning nozzle in the uppermost compartment, piping establishing communication between the compartments, an air inlet to one compartment and 40 an outlet from another compartment, and means whereby an extraneous fluid medium can be introduced into the piping.

14. Apparatus for spinning cellulose ethers or esters, comprising a spinning cell, 50 means dividing the cell into superimposed compartments to be successively traversed by the spun thread, a spinning nozzle in the uppermost compartment, piping establishing communication between the compartments, an air inlet to one compartment and 55 an outlet from another compartment, a heat exchanger associated with the piping, and means whereby an extraneous fluid medium can be introduced into the piping.

60 15. Apparatus for spinning cellulose ethers or esters, comprising a spinning cell, a diaphragm dividing the cell into two superimposed compartments to be successively traversed by the spun thread, a spinning 65 nozzle in the upper compartment, an air in-

let to the upper compartment located adjacent the nozzle, an air and solvent vapor outlet from the lower compartment, a pipe establishing communication between the lower portions of said compartments, and a heater 70 for the pipe.

16. Apparatus for spinning cellulose ethers or esters, comprising a spinning cell, a diaphragm dividing the cell into two superimposed compartments to be successively traversed by the spun thread, a spinning nozzle in the upper compartment, an air inlet to the upper compartment located adjacent the nozzle, an air and solvent vapor outlet from the lower compartment, a pipe 75 establishing communication between the lower portions of said compartments, a heater for the pipe, and means whereby an extraneous fluid medium can be introduced into the pipe.

In testimony whereof I affix my signature.
MELITTA KLEIN.
